UNITED STATES PATENT OFFICE.

WILLIAM C. CARVER, OF TULSA, OKLAHOMA.

AUTOMATIC LANTERN-SLIDE-PROJECTING MACHINE.

1,165,318.

Specification of Letters Patent.

Patented Dec. 21, 1915.

Application filed February 24, 1915. Serial No. 10,345.

To all whom it may concern:

Be it known that I, WILLIAM C. CARVER, a citizen of the United States, residing at Tulsa, in the county of Tulsa and State of Oklahoma, have invented new and useful Improvements in Automatic Lantern-Slide-Projecting Machines, of which the following is a specification.

The invention relates to machines for projecting pictures, and has for an object to provide a means for automatically projecting a series of pictures, such as lantern slides or the like, upon a suitable curtain or screen.

The invention contemplates, among other features, the provision of a device for automatically projecting upon a curtain or screen a succession of pictures or slides which are automatically fed into projecting position and automatically removed from projecting position, the invention to this end contemplating various improvements in lantern slide projecting machines embodied in an application for United States patent, entitled "Automatic lantern slide projecting machine", filed by me December 2, 1914, Serial No. 875,149.

In the ordinary use of a projecting machine it is customary to insert and remove the slides from projecting position by hand or by means of a sliding holder which is of a duplex nature in that it can accommodate two and sometimes more slides at one time for successive projection. In my device I aim to provide a structure which permits of the successive projection of slides upon screens, the arrangement of the slides prior to and after projection being such that the slides will be automatically carried into projecting position and automatically removed therefrom, the invention to this end embodying the use of a driving medium for a slide operating mechanism which may be either of a constant or intermittent operation to accomplish the desired result.

In the further disclosure of the invention reference is to be had to the accompanying drawings, constituting a part of this specification, in which similar characters of reference denote corresponding parts in all the views, and in which:

Figure 1 is a vertical longitudinal sectional view taken through the machine showing a slide for exhibiting position; Fig. 2 is a similar view showing the slide removed from exhibiting position and being advanced toward the slide holder or container; Fig. 3

is a vertical transverse sectional view taken on the line 3—3 in Fig. 1; Fig. 4 is a horizontal sectional view taken on the line 4—4 in Fig. 1; Fig. 5 is a fragmentary vertical longitudinal sectional view similar to what is shown in Figs. 1 and 2, showing the manner of tripping the slide to permit the same to pass into the slide holder or container; Fig. 6 is a perspective view of one of the slides; Fig. 7 is a fragmentary enlarged vertical sectional view showing a modified form of slide operating member; Fig. 8 is a horizontal sectional view taken on the line 8—8 in Fig. 7; and Fig. 9 is a fragmentary vertical transverse sectional view of a modified slide actuating mechanism.

Referring more particularly to the views, I provide a casing 10 which is preferably made in two sections 11 and 12 suitably hinged together, with the front section 11 carrying the usual projecting apparatus 13 and a driving element 14, the rear section 12 having a platform 15 upon which is carried the illuminating member 16 for supplying light to the projecting apparatus. The front section has a series of toothed wheels 17 journaled therein and over which pass a chain-like slide advancing member 18, this construction being somewhat similar to what is shown in the co-pending application mentioned heretofore and consisting, more particularly, of a plurality of continuous chains 19 which, through the medium of suitable connecting elements 20, are geared with or connected to the driving element 14 so as to result in either an intermittent or continuous operation of the slide advancing member. A series of projections 21 in the nature of platforms extend from the chains 19 of the slide advancing member and are adapted to engage a slide 23, said slide having pins 22 projecting therefrom and which are adapted to operate in guideways 22^a formed in the sides of the casing.

The front of the rear section is in the nature of a closure for the rear of the front section and carried on the front of the rear section near its lower end and in alinement with the projecting apparatus 13 is a slide supporter 24 formed in the nature of a casing and which supports the slide in interposed position between the projecting apparatus and the illuminating member 16 so that the projection of the slide upon the screen will be properly insured. Connecting with the slide supporter and extending up-

wardly therefrom is a curved chute 25, the upper end of which is disposed adjacent to a suitable platform 26 preferably provided with an opening 27, said platform, further-
5 more, connecting with a slide container 28 in which a number of the slides 23 are arranged in superposed position.

Now referring to the views, it will be clearly seen that when the slide advancing mechanism 18 is actuated, the projections 21 thereon will engage the slide in the slide supporter and remove the slide from the slide supporter to raise the same upwardly to the entrance of the slide container 28, a
10 suitable ledge 30 being provided on the slide container 28 to trip the slide in order to remove it from the slide advancing mechanism and permit the slide to gravitate down an inclined plane 31 into the slide container.

20 It will be seen that the slide is guided by the pins 22 operating in the guideways 22^a, the slide being supported by the platforms 21 projecting from the chains 19, as clearly shown in Fig. 2, and that the ledge 30 will aid in tilting the slide when it reaches the upper end or entrance to the container, said slide, however, being guided in its tilting movement by the wall of the container.

Suitably journaled to rotate in the front section 11 of the casing 10 is a wheel-like member 32 connecting with the slide advancing mechanism 18 to be rotated thereby, said member 32 carrying a projecting pin or knob 33 which is adapted to engage the forward end of a spring-engaged plunger 34 so that the head end 35 of said plunger, when the same is operated against the action of the spring, will pass into the lower end of the slide container 28 and advance the lowermost slide in the container from the platform 26, through the opening 27 into the chute 25 and thence gravitate into the slide supporter 24, the slide being then in exhibiting position. When the slide has been exhibited the desired length of time and which length of time depends entirely upon the speed of rotation of the slide advancing mechanism or its intermittent or constant movement, a plurality of the projections on the said slide advancing mechanism will engage the slide and, raising the same from the supporter, will remove it from projecting position and advance the same to the entrance of the slide container. At this point the slide will be tripped by the ledge and the wall of the container, which the slide engages, as mentioned heretofore, and be deposited in the slide container. As shown, the slide container is provided with a filling opening 28^a to insure proper loading of the container prior to operating the machine for the purpose of projecting the desired slide upon the screen.

From the foregoing description it will be seen that with a machine of the character

described it is only necessary for the operator to initially load the slide container and then set the machine in operation. The first slide is now moved from the slide container by the plunger and which is automatically operated by the member 32, said slide being advanced into the chute to gravitate into the slide supporter and at which time the slide will be exhibited, in order that its representation will be properly depicted upon the screen or curtain. The slide advancing mechanism is so timed or operated that when the slide has been exhibited the desired length of time it will be automatically grasped by the slide advancing mechanism and carried upward to be deposited in the slide container, while at the same moment and in a proportionate amount of time the plunger will be again actuated to advance the next slide from the slide container on to the platform and thence into the chute from which the next slide container will gravitate into the slide supporter to be exhibited. In this manner the operation of the machine is continued until all of the slides have been exhibited, and it will be clearly seen that with a machine of the character described the work of the operator is greatly reduced; the exhibition of the pictures will be more uniform and the result more effectively accomplished.

As mentioned heretofore, I preferably have the slide advancing mechanism constructed somewhat on the lines of the chain-like slide carrying mechanism shown in my application filed December 2, 1914, although it will be clearly understood that I do not limit myself to the particular form shown and that various slight changes may be made from the construction set forth in the drawings without departing from the spirit of the invention.

In Figs. 7 and 8 I show a slightly modified form of my invention and in which instance, instead of the plunger 34, I provide a rod 36 pivoted to the member 32 and which rod 36 is in pivotal engagement with a sliding and tilting tray 37 having upwardly extending ledges 38 adapted to engage the lowermost slide 23 which will be deposited in the tray, the tray being then tilted so that the slide can pass down the chute into the slide exhibiting casing 24. Projecting from the sides of each slide 23 are plates 39 which are engaged by the ledges 38 when the tray 37 slides forwardly in the container, a tilting plate 40 being arranged to extend horizontally across the casing 28 from each side to hold the lowermost slide against movement into the tray until the slide is tilted on the edge of the tilting plate when the slide is moved forwardly by the ledges 38. It will be noted that the guideways 22^a also extend into the slide container to insure the proper gravita-

tion of the slide into position within the container when the same is removed from the slide advancing member, the pins 22 projecting from the slide being arranged to operate in said guideways as will be readily understood.

In Fig. 9 I show a modified form of slide operating mechanism taking the place of what is shown in Fig. 7 and in this instance

10 it will be seen that there is a horizontal shaft 41 carrying a toothed wheel 42 over which operates a chain 42^a connecting with the usual chain operating mechanism or driving member shown in Figs. 1 and 2, the 15 ends of the shaft 41 carrying beveled toothed wheels 43 meshing with beveled toothed wheels 44 on vertical shafts 45, each of which is formed with a worm or spiral conveyor 46, the shafts 45 being suitably journaled in the frame or casing of the machine. Now it will be seen that the plates 23 will be supported by the spiral conveyors 46 and in view of the fact that the toothed wheel 42 is geared with respect to the driving member to a certain proportion, the spiral conveyors will be rotated a complete revolution at certain intervals and each time that the spiral conveyors rotate a revolution the lowermost 25 slide 23 supported by the lowermost 30 convolution of the conveyors will be dropped therefrom and will thus slide down the incline or chute 25, the structure shown in Fig. 7 and indicated by the numerals 32, 36, 37 and 40 being in this instance dispensed 35 with as is also the platform or ledge 26 shown in Fig. 5. Therefore, with the structure shown in Fig. 9 the slide, when dropped by the conveyors, will gravitate down the chute and into position in front of the 40 densing lens of the machine.

Having thus described my invention, I claim:

1. A lantern slide projecting machine comprising a casing, a projecting apparatus in 45 said casing, a slide supporter disposed in the line of projection of said apparatus, a slide container, a combined platform and chute connecting said slide container with said slide supporter for assuring the advancement of a slide from the container to the 50 supporter, means automatically operated for removing the slide from the container and initially advancing the said slide toward the supporter, and means for periodically operating said last-named means.

2. A lantern slide projecting machine comprising a casing, a projecting apparatus in said casing, a slide supporter disposed in the line of projection of said apparatus, a 60 slide container, a combined platform and chute connecting said slide container with said slide supporter for assuring the advancement of a slide from the container to the supporter, means automatically operated for removing the slide from the con-

tainer and initially advancing the said slide toward the supporter, means for periodically operating said means, and a slide advancing mechanism for engaging and removing an exhibited slide in the supporter therefrom 70 and advancing said slide to said slide container, said means for operating said first-named means having connection with said slide advancing mechanism.

3. A lantern slide projecting machine 75 comprising a casing, a projecting apparatus in said casing, a slide supporter disposed in the line of projection of said apparatus, a slide container, a combined platform and chute connecting said slide container with 80 said slide supporter for assuring the advancement of a slide from the container to the supporter, means automatically operated for removing the slide from the container and initially advancing the said slide toward 85 the supporter, means for periodically operating said means, a slide advancing mechanism for engaging and removing an exhibited slide in the supporter therefrom and advancing said slide to said slide container, said means for operating said first-named means having connection with said slide advancing mechanism, and means for removing the slide from the slide advancing mechanism to permit of said slide being advanced 90 back into said slide container.

4. A lantern slide projecting machine comprising a casing, a projecting apparatus in said casing, a slide supporter disposed in the line of projection of said apparatus, a slide container, a combined platform and chute connecting said slide container with 100 said slide supporter for insuring the advancement of a slide from the container to the supporter, a plunger for removing the 105 slide from the container and initially advancing the slide toward the supporter, and means for periodically operating said plunger.

5. A lantern slide projecting machine 110 comprising a casing, a projecting apparatus in said casing, a slide supporter disposed in the line of projection of said apparatus, a slide container, a combined platform and chute connecting said slide container 115 with said slide supporter for insuring the advancement of a slide from the container to the supporter, a plunger for removing the slide from the container and initially advancing the slide toward the supporter, 120 means for periodically operating said plunger, and a slide advancing mechanism for engaging and removing an exhibited slide in the supporter therefrom and advancing said slide to said slide container, said means for 125 operating said plunger having connections with said slide advancing mechanism.

6. A lantern slide projecting machine comprising a casing, a projecting apparatus in said casing, a slide supporter disposed in 130

the line of projection of said apparatus, a slide container, a combined platform and chute connecting said slide container with said slide supporter for insuring the advancement of a slide from the container to the supporter, a plunger for removing the slide from the container and initially advancing the slide toward the supporter, means for periodically operating said plunger, a slide advancing mechanism for engaging and removing an exhibited slide in the supporter therefrom and advancing said slide to said slide container, said means for

operating said plunger having connection with said slide advancing mechanism, and means for removing the slide from the slide advancing mechanism to permit of said slide being advanced back into said slide container.

In testimony whereof I affix my signature in presence of two witnesses.

WILLIAM C. CARVER.
